CLAIM

The ornamental design for a head shield for golf bag, as shown and described.

DESCRIPTION

FIG. 1 is a perspective view of the head shield for golf bag of my invention;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a sectional view, taken along the line 8—8 shown in FIG. 6; and,

FIG. 9 is a perspective view thereof on a reduced scale in position of use with a golf bag which is shown in broken lines for illustrative purposes and forms no part of the claimed design.
